ECCENTRICALLY DISPOSED MALE AND FEMALE SPLINE TEETH

BACKGROUND OF THE INVENTION

The mating female and male spline teeth at the opposite ends of a wobble shaft which interconnects an orbiting fluid rotor and a rotatable valve, in a fluid pressure device, are subject to wear due to the fact that the reversal of the spheroidal rubbing action between the mating spline teeth always occurs at the same place, cycle after cycle. The wear may be considered in terms of molecular fatigue, resulting from the reversal of the rubbing action occurring at the same location at the end of each orbital cycle. Where one end of the wobble shaft is pivoted about a fixed point, as is the case in the prior art, the same set of male and female molecules contact each other, at the point of the reversal, six times per revolution of the wobble shaft. The molecular fatigue may be likened to that of bending the free end of a wire at the same spot to break it off as compared to bending it over a distributed section where it takes longer to break it off.

In this invention, the fatigue of the spline teeth is distributed, whereby the same set of male and female molecules do not contact each other at the same place at the end of each reversal of the rubbing action, but contact each other only once per revolution of the wobble shaft, as compared to six times per revolution as is the case in the prior art.

Accordingly, it is an object of my invention to shift the location of the fatigue of the spline teeth at the end of each reversal of the rubbing action over a distributed area.

Another object is to distribute the wear between the mating female and male spline teeth, whereby the same set of male and female molecules do not contact each other at the same place at the end of each reversal of the spheroidal rubbing action, but contact each other only once per revolution of the wobble shaft, as compared to six times per revolution, as is the case in prior art.

Another object is to provide an eccentric pivot for one end of the wobble shaft instead of a fixed pivot.

Another object is the provision of eccentrically disposed male and female spline teeth having unlike contact engagement therebetween from one succeeding set of teeth to the next and like contact engagement therebetween only once per revolution.

Another object is to limit the extent that the male and female mating spline teeth may move in an axial direction relative to each other.

SUMMARY OF THE INVENTION

The invention constitutes eccentrically disposed male and female spline teeth having unlike contact engagement therebetween from one succeeding set of teeth to the next and like contact engagement therebetween only once per revolution.

Other objects and a fuller understanding of this invention may be had by referring to the following description and claims, taken in conjunction with the accompanying drawings, in which:

FIG. 1 is an elongated, partial sectional view of a fluid pressure device embodying the features of my invention;

FIG. 2 is a representation of a male shank provided on the terminal end portion of a hollow shaft adapted to fit within a female socket of a rotary valve;

FIG. 3 is a view taken along the line 3—3 of FIG. 1, under the end cap, showing the stator-rotor mechanism;

FIG. 4 is a cross sectional view of the main shaft and the wobble shaft only taken along the line 4—4 of FIG. 1, the view illustrating the fact that the female spline teeth are eccentrically disposed with reference to the axis of the main shaft;

FIG. 5 is a view similar to FIG. 4, but illustrating the fact that the male spline teeth are eccentrically disposed with reference to the axis of the wobble shaft;

FIG. 6 is an illustration showing the condition where the left-hand end of the wobble shaft is pivoted about a fixed axis, as is the case in the prior art, wherein it is noted that the same angulated position of the wobble shaft repeats itself at the end of each cycle;

FIGS. 7 to 12 are views similar to FIG. 6, but show the condition where the left-hand end of the wobble shaft is eccentrically pivoted about the axis of the main shaft, wherein it is noted that the same angulated position of the wobble shaft is not repeated until the wobble shaft makes one complete revolution which comprises six orbital cycles.

DESCRIPTION OF THE PREFERRED EMBODIMENT

With reference to the drawing, the fluid pressure device in which my invention may be incorporated, comprises generally a hollow housing 20 having substantially a square cross-section. A mounting flange or end plate 21 may be secured to the left-hand end of the housing. Intermediate the ends of the hollow housing 20, there is provided an annular internal rim 22 which generally separates the hollow housing into a left-hand end compartment and a right-hand end compartment. Rotatively mounted in the left-hand end compartment is a main shaft 25 having a fixed axis 69 substantially coinciding with the longitudinal axis of the fluid pressure device. A bushing 27 and a rotary valve 28 are mounted in the right-hand end compartment. On the right-hand end of the hollow housing, there is mounted a square stationary valve member 29 by means of suitable screws 30. The rotary valve 28 is adapted to be rotated relative to the stationary valve member 29 for controlling the entrance of fluid to and the exit of fluid from a stator-rotor mechanism 31 comprising a stator 32 and a rotor 33. An end cap 34 encloses the stator-rotor mechanism 31. The entrance of fluid to and the exit of fluid from the stator-rotor mechanism flows through a plurality of fluid openings 40 in the stationary valve member 29 controlled by the rotation of the rotary valve 28. The stator-rotor mechanism 31 and the end cap 34 are secured to the stationary valve member 29 by means of screws 35. Fluid is delivered to and from the housing 20 through a pair of fluid ports 23 and 24. An orbital or wobble shaft 36 interconnects the main shaft 25 with the rotor 33 of the stator-rotor mechanism 31 and is adapted to transmit torque therebetween.

The main shaft 25 comprises an enlarged internal portion having a reduced external portion 41 extending axially outwardly of the hollow housing 20 through the

mounting flange 21. The enlarged internal portion of the main shaft is supported preferably by tapered roller bearings, generally indicated by the reference character 42. A tightening nut 54 which threadably engages male threads 55 secures the bearings 42 against axial movement upon the main shaft.

The tapered bearings constitute common bearing means for the main shaft and the rotary valve, and thus the main shaft and the rotary valve are disposed for rotation about the same fixed axis 69. The common bearing means directly support the main shaft 25 and indirectly support the rotary valve 28 through extension drive means comprising a hollow shaft 44 integrally connected to the main shaft. The hollow shaft 44 extends into the right-hand compartment and supportingly rotates the rotary valve 28 relative to the stationary valve member 29. The hollow shaft 44 terminates in a male shank 45 which slidably fits within a female socket provided in the rotary valve 28. This connection comprises a non-rotatable connection and rotates the rotary valve upon rotation by the main shaft.

Although not limited thereto, the stator 32 has seven internal teeth and the rotor 33 has six external teeth. The intermeshing teeth upon relative movement therebetween define operating fluid chambers. The rotor has an axis 70 which orbits about a fixed axis 69 of the stator, being the same fixed axis about which the main shaft and the rotary valve rotate. The rotor also rotates about its own axis. The orbital shaft 36, which interconnects the rotor 33 and the main shaft 25 is disposed to drive the rotary valve 28 relative to the stationary valve member. The right-hand end of the orbital shaft 36 has an operative connection with the rotor 33 and comprises male spline teeth 71 fitting within female spline teeth 72 of the rotor. The left-hand end of the orbital shaft 36 has an operative connection with the main shaft 25 and comprises male spline teeth 73 fitting within female spline teeth 74 in the main shaft. As illustrated in FIG. 4, the female spline teeth 74 have a center 53 which is eccentrically disposed with reference to the fixed axis 69. The eccentricity need be only a small amount, sufficient to cause a mismatching of the molecules and may reside in a range varying from approximately 5 percent to 50 percent of the eccentricity of the rotor 33. Thus, the left-hand end of the orbital shaft 36 is disposed for eccentric movements about the fixed axis 69, while the right-hand end is disposed for both orbital and rotational movements, partaking that of the orbital and rotational movements of the rotor 33.

The stationary valve member 29 has first and second side wall means 38 and 39, with the first side wall means 38 held in facing relationship to the inside face of the stator-rotor mechanism. The second side wall means 39 defines a reference plane against which the rotary valve sealingly engages. The reference plane is also identified by the same number as that for the second side wall means. Extending through the stationary valve member 29, is a shaft opening 52. The orbital shaft 36 extends through the shaft opening 52 and has a shaft axis 51 defining an orbit angle with respect to the fixed axis 69. The right-hand end of the shaft axis 51 meets with the rotor axis 70, and partakes of the same movement. The orbital shaft 36 makes a rota-

tional movement about its own shaft axis 51 and an orbital movement about the fixed axis 69.

The stationary valve member 29 in FIG. 1 shows an inclined stop-limit surface 47 extending outwardly of the shaft opening 52. Extending outwardly of the orbital shaft 36, is a shoulder 48 which has a flat, inclined limit surface 49 disposed to abutably engage the stop-limit surface 47 to limit relative axial movement between the male and female spline teeth. Accordingly, the male and female spline teeth 73 and 74 are kept in full axial engagement with each other.

Since the stator 32 has seven internal teeth and the rotor 33 has six external teeth, the rotor 33 orbits six times about the fixed axis 69 for each rotation of the wobble shaft 36 about its own axis 51. Thus, in FIG. 6, where the left-hand end of the wobble shaft is illustrated as being pivoted about the fixed axis 69, as is the case in the prior art, it is to be observed that the same 15 angulated position of the wobble shaft repeats itself at the end of each cycle, which is six times per revolution of the wobble shaft, as represented by the six black dots 75. The circle 44 in FIG. 6 represents the hollow shaft 44 which supportingly rotates the rotary valve 28. The 20 intervals between the six-black-dots represent the amount that the rotary valve rotates per each orbital cycle. In FIG. 6, the reversal of the spheroidal rubbing action of the male and female spline teeth occurs at the same location at the end of each orbital cycle, because the angulated position of the wobble shaft repeats itself at the end of each cycle. Thus, the same set of male and 25 female molecules are fatigued six times per revolution of the rotary valve 28.

FIGS. 7 to 12 illustrate the situation in my invention, 30 where the same set of male and female molecules are fatigued only once for each revolution of the rotary valve 28, which means that the fatigue at the same spot has been reduced by one-sixth. FIG. 7 shows the angulated position of the wobble shaft at the start of the first 35 orbit, where the black-dot 75, representing the position of the rotary valve 28, is at zero degrees with respect to the vertical. FIG. 8 shows the angulated position of the wobble shaft at the start of the second orbit, where the black-dot 75, representing the position of the rotary 40 valve 28, is at 60° with respect to the vertical in a clockwise direction, which rotation is opposite in direction to that of the orbit movement.

FIGS. 9 to 12 progressively show the angulated position of the wobble shaft at the start of each succeeding cycle, where it is noted that the angulated position of the wobble shaft does not repeat itself until the rotary 45 valve makes one complete revolution, being at the starting position as shown in FIG. 7.

The action above described illustrates the fact that the reversal of the spheroidal rubbing of the male and female spline teeth repeats itself only once per revolution of the wobble shaft or rotary valve, instead of six times, as is the case in the prior art. The fatigue is thus 50 distributed, which means that the wear qualities of the male and female spline teeth are improved. It is also to be observed that, since the wobble shaft is limited against axial movement to the right, the contact engagement of the male and female spline teeth, so far as 55 axial contact is concerned, repeats itself only once per revolution of the rotary valve. Thus, the male and female spline teeth, so far as the axial mismatching of

the molecules is concerned, have a small amount of relative axial movement therebetween, which repeats itself only once per revolution. The axial mis-matching also improves the wear qualities.

Although this invention has been described in its preferred form with a certain degree of particularity, it is understood that the present disclosure of the preferred form has been made only by way of example and that numerous changes in the details of construction and the combination and arrangement of parts may be resorted to without departing from the spirit and the scope of the invention as hereinafter claimed.

What is claimed is:

1. A torque transmitting device, including rotor means having a rotor axis and rotatable means having a fixed axis, shaft means operatively interconnecting said rotor means and said rotatable means, said rotor means having a combined movement comprising an orbital movement about said fixed axis and a rotational movement about its own axis, said orbital movement being at a first speed about said fixed axis and said rotational movement being at a second speed about said rotor axis, said shaft having a shaft axis and first and second shaft portions axially spaced apart from each other along said shaft axis, said first shaft portion being operatively connected to and having a combined movement partaking that of said rotor means, said second shaft portion being operatively connected to said rotatable means for orbital movement relative to said fixed axis, said rotor means having first female spline

30

teeth therein encircling said rotor axis, said first shaft portion having first male spline teeth thereon encircling said shaft axis, said first female spline teeth and said first male spline teeth being of the same number, all of said first male spline teeth respectively fitting within and respectively making contact with all of said first female spline teeth to provide a rotational shaft speed the same as said second speed of said rotor means, said rotatable means having second female spline teeth therein encircling said fixed axis, said second shaft portion having second male spline teeth thereon encircling said shaft axis, said second female spline teeth and said second male spline teeth being of the same number, all of said second male spline teeth respectively fitting within and respectively making contact with all of said second female spline teeth, said second female spline teeth eccentrically encircling said fixed axis for orbiting said second shaft portion about said fixed axis at said second speed.

2. The structure of claim 1, wherein said second speed is slower than said first speed.

3. The structure of claim 1, wherein said rotatable means includes valve means.

4. The structure of claim 1, wherein said male and female spline teeth have substantially spheroidal contact engagement therebetween.

5. The structure of claim 1, having axis limit means to limit the extent that said male and female spline teeth may axially move relative to each other.
